UNITED STATES PATENT OFFICE.

WILLIAM F. COMISKY, OF MIDDLETOWN, CONNECTICUT.

SHUTTLE.

1,201,150.

Specification of Letters Patent. Patented Oct. 10, 1916.

Application filed January 27, 1916. Serial No. 74,610.

To all whom it may concern:

Be it known that I, WILLIAM F. COMISKY, a citizen of the United States, and a resident of Middletown, in the county of 5 Middlesex and State of Connecticut, have invented a new and Improved Shuttle, of which the following is a specification.

My invention relates to the class of devices above named, and an object of my invention, among others, is to provide a device of this kind having means to effectively support a bobbin in a manner to prevent the thread from "sloughing" off.

One form of device embodying my invention, and in the construction and use of which the objects herein set out, as well as others, may be attained, is illustrated in the accompanying drawings, in which—

Figure 1 is a side view of a shuttle embodying my invention, with parts broken away to show construction. Fig. 2 is a view looking at the shuttle from a point located at right angles to the point of view of Fig. 1. Fig. 3 is a view in cross section through 25 the shuttle on plane denoted by dotted line 3—3 of Fig. 1, the bobbin being removed. Fig. 4 is a detail view showing a slightly different construction of means for attaching the spring to the base.

In the operation of weaving, as is well understood, the shuttle is thrown with great force and is suddenly brought to a stop at each end of its path of travel with a result that the thread must be wound securely upon 30 the bobbin and the bobbin must be securely fastened in place to withstand such force, and in the uses of some kinds of thread, and particularly silk, it is almost impossible to prevent the silk from "sloughing" off from 35 the end of the bobbin by reason of the sudden stopping of the shuttle in its travel.

It is a purpose of my present invention to provide means for resiliently supporting the bobbin so that the jars and vibrations incident to the sudden stopping of the shuttle will not be sufficient to remove the thread from the bobbin or the bobbin from the spindle, these means of support being so constructed that they will also effectively 40 resist the force incident to such action. Such a device is shown in the accompanying drawings in which the numeral 5 indicates a shuttle case having a recess 6 within which a base 7 is rotatably mounted upon a pivot 8, said base being held in predetermined positions by means of a spring 9, a

spindle 10 projecting from the end of the base.

All of the parts thus far described are of old and well known construction, and, except in connection with the parts to be hereinafter described, constitute no part of my present invention.

In carrying out my idea a spring is secured to the side of the base to provide a resilient support for a bobbin on the spindle, in one form of device this spring being attached by means of a clip 11 that is removably secured to one side of the base 7. A backturned part 12 from the clip provides a space within which the end of the outer coil 13 of the spring is received and within which it is clamped and securely held by causing said back turned part to firmly bind the end of the spring in any suitable manner. This spring is preferably formed of flat metal of considerable width preferably disposed in conical form as shown in Fig. 1 of the drawings, it being noted that the spring is under full compression and that if relieved the side toward the base would assume a conical form as well as the opposite side. A sleeve 14 projects through the inner coil of this spring, a flange 15 on this end of the sleeve resting against the coils of the spring. This sleeve is provided with a swelled portion 16 to fit snugly within the quill 17 of the bobbin to hold the latter in place by frictional engagement, this sleeve and the quill being of well known construction.

The clip 11 is secured in place as by means of a screw 18 threaded into the base 7, said screw passing through a slot 19 in said clip. A tensioning lip 20 may be formed on the end of the clip to engage the edge of the base, or with tensioning shoulders constituted by grooves 21 in the side of the base, so that the clip may be placed in various positions, and the apex of the cone of the spring resting against the base, this change of the position of the clip will regulate the tension of the spring. A spring holding plate 22 may be secured in place by the screw 18, the end of this plate, when employed, resting against the edge of the spring and holding it from displacement within the backwardly turned part of the clip. The end of the spring may be enlarged as at 23, in any suitable manner to prevent its withdrawal endwise of the spring from underneath said backturned

part of the clip. The quills 17 forming the center of the bobbins are commonly made of paper, and owing to the clinging character thereof upon the sleeve and the yielding action of the latter owing to the spring that holds it in place, it is a difficult matter many times to remove the bobbin by a straight pull. By giving a slight twist to the bobbin, however, its removal from the sleeve 14 may be easily accomplished. In order to effect this purpose and permit a relative turning movement of the bobbin with respect to the sleeve, I provide means for holding the latter. In one form of construction I produce this result by making the spindle of angular shape at its base, 24, the square form being preferable, and by making the sleeve 14 of corresponding shape to fit the spindle at this point as shown in Fig. 3 of the drawings, the sleeve will be held from turning movement with the quill when the latter is twisted to loosen it. This result may be attained in many different ways that will readily suggest themselves to those skilled in the art.

In Fig. 4 of the drawings there is shown a clip 26 that is formed integral with the spring as one means for securing the latter to the base 7, it being my purpose to use this form of clip with the device shown in Figs. 1 and 2 if desired.

While I have shown and described herein a satisfactory construction of device embodying my invention, this may be departed from to a greater or lesser degree and yet be within the spirit and intent of the invention.

I claim—

1. In a shuttle, a case, a base secured within the case, a spring composed of flat metal arranged in a coil, means for securing one end of the spring to the base, a bobbin sleeve projecting through the center of said coil and having means to prevent its disengagement from said coil, and means for otherwise supporting the bobbin.

2. In a shuttle, a case, a base secured within the case, a spring composed of flat metal arranged in a coil of conical form with the apex pressing against the base, means for securing the outer end of the spring to the base, a bobbin sleeve projecting through the center of the coil and having means to prevent its disengagement therefrom, means for varying the pressure of the spring against the base, and means for otherwise supporting the bobbin.

3. In a shuttle, a case, a base located within the case, a coiled spring located opposite the end of the base and having a projecting part secured to the side of the base, a bobbin sleeve projecting through the center of the spring and having means to prevent its disengagement therefrom, and means for otherwise supporting the bobbin.

4. In a shuttle, a case, a base located within the case, a coiled spring composed of flat metal located opposite the end of the base and having a projecting part secured to the side of the base, a bobbin sleeve projecting through the center of the spring and having means to prevent its disengagement therefrom, and means for otherwise supporting the bobbin. 70

5. In a shuttle, a case, a base located within the case, a spindle projecting from the end of the base, a coiled spring surrounding said spindle and having a projecting part secured to the side of the base, and a bobbin sleeve projecting through the center of the spring and surrounding said spindle. 75

6. In a shuttle, a case, a base located within the case, a spring, a clip having an overturned lip to engage and secure the outer end of the spring, means for securing the clip to the base, a bobbin sleeve projecting through the center of the spring and having means to prevent its disengagement therefrom, and means for otherwise supporting the bobbin. 80

7. In a shuttle, a case, a base secured within the case, a clip secured to said base and having an overturned lip, a spring composed of flat metal spirally arranged in conical form, means for securing the outer end of the spring to the clip, a bobbin sleeve projecting through the center of the spring and having means to prevent its disengagement therefrom, and means for otherwise supporting the bobbin. 85

8. In a shuttle, a case, a base secured within the case, a clip having an overturned lip, a spring having its outer end located underneath said clip, a holding plate to close the mouth of the opening to said clip and prevent removal of the spring, a bobbin sleeve projecting through the center of the spring and having means to prevent its disengagement therefrom, and means for otherwise supporting the bobbin. 90

9. In a shuttle, a case, a base secured within the case, a clip mounted on the base and adjustable lengthwise of the case, a spring arranged in a spiral of conical form with the apex of the cone resting against the base, means for securing the outer end of the spring to the clip, a bobbin sleeve projecting through the center of the spring and having means for preventing its disengagement therefrom, and means for otherwise supporting the bobbin. 105

10. In a shuttle, a case, a base secured within the case, a clip having an adjusting lip, means to engage said lip in different positions of the clip, means for securing the clip, a spring arranged in a spiral of conical form with the apex of the cone resting against the base, means for securing the outer end of the spring to the clip, a bobbin sleeve passing through the center of the 115

spring and having means to prevent its disengagement therefrom, and means for otherwise supporting the bobbin.

11. In a shuttle, a case, a base secured 5 within the case, said base having grooves providing adjusting shoulders, a clip having an adjusting lip to engage said shoulders, means for securing the clip in different positions, a spring arranged in a spiral of 10 conical form with the apex of the cone resting against the base, means for securing the outer end of the spring to the clip, a bobbin sleeve passing through the center of the spiral and having means for preventing its 15 disengagement therefrom, and means for otherwise supporting the bobbin.

12. In a shuttle, a case, a base secured within the case, a clip having an overturned lip and an adjusting lip, means on the base 20 to engage said adjusting lip in different positions, a holding plate to close the mouth to said overturned lip, a screw to secure said plate and clip in place, a spring having one end secured underneath said overturned lip, 25 said spring being arranged in a spiral of conical form with the apex of the cone resting against said base, a bobbin sleeve projecting through the center of the spring and having means to prevent its disengagement 30 therefrom, and means for otherwise supporting the bobbin.

13. In a shuttle, a case, a base secured within the case, a clip having an overturned lip, means for securing the clip in different

positions lengthwise of the case, a spring 35 composed of flat metal arranged in a spiral of conical form, one end of said spring being secured underneath said overtured lip, a holding plate secured to the clip to retain said spring underneath said lip, a bobbin 40 sleeve projecting through the center of the spring and having means to prevent disengagement therefrom, and means for otherwise supporting the bobbin.

14. In a shuttle, a case, a base secured 45 within the case, a coiled spring secured by the base, a sleeve held by said spring, a bobbin including a quill removable from but frictionally secured to the sleeve, and means to permit relative turning movement of the 50 quill with respect to the sleeve.

15. In a shuttle, a case, a base secured within the case, a coiled spring secured by the base, a sleeve held by said spring, a bobbin including a quill removable from but 55 frictionally secured to the sleeve, and means to prevent turning movement of the sleeve with respect to said base.

16. In a shuttle, a case, a base secured within the case, a spindle projecting from 60 the base, a coiled spring surrounding said spindle and secured to the base, a sleeve surrounding the spindle within the spring, and means for securing the sleeve against turning movement with respect to the spindle 65 while permitting independent movement thereof endwise of the spindle.

WILLIAM F. COMISKY.
